VENTILATING DEVICE

Louis J. Jenn, Indianapolis, Ind.

Application January 26, 1953, Serial No. 333,140

4 Claims. (Cl. 98—116)

This invention relates to a ventilating device for a room or building, and while the same might have various applications, it is particularly designed to be attached to a wall and to draw air through a passage in said wall.

It is an object of this invention to provide a very simple, compact and efficient ventilating device which can be easily assembled and disassembled and which can be very easily installed in operative position in conjunction with a passage extending through a wall.

It is also an object of this invention to provide a ventilating device comprising a member or housing of semi-dome shape and having a peripheral flange adapted to be secured against a wall about a passage therethrough, a second member having an outer substantially semi-spherical portion having an outwardly extending cylindrical portion cooperating with a conduit extending through said passage, brackets secured to said second member, a plate secured to said brackets and a motor secured to said plate, said motor having a fan secured to its driving shaft and disposed within said semi-spherical portion.

It is more specifically an object of the invention to provide a ventilating device cooperating with a conduit extending through a passage in a wall, said device comprising a member or housing having a concave annular portion with its concave side directed toward said conduit and wall and having a peripheral flange adapted to be secured to said wall, a second member having a substantially semi-spherical portion with its concave side directed outwardly away from said wall, the outer portions of said members being in engagement and secured together, said second member having a cylindrical portion extending into said passage and conduit, spaced supporting means secured to said semi-spherical portion and extending outwardly therefrom, a plate secured to said supporting means, a motor secured to said plate having its driving shaft directed toward said conduit, a fan secured to said shaft and disposed within said semi-spherical portion and a cover secured to said plate surrounding and spaced from said motor.

These and other objects and advantages of the invention will be fully set forth in the following description made in connection with the accompanying drawings in which like reference characters refer to similar parts throughout the several views and in which:

Fig. 1 is a central vertical section through the device and the wall to which it is secured; and

Fig. 2 is a view in elevation as seen from the left of Fig. 1.

Referring to the drawings, a device is shown adapted to be connected to a wall 10. Said wall has a passage 10a therethrough shown as of cylindrical form. A conduit 11 fits in and is disposed in passage 10a, the same having a peripheral flange 11a at its outer side which will be secured to the outer side of wall 10 in any suitable manner, as by a plurality of circumferentially spaced screws 12. A support 14 is provided, and while this might be of various forms, in the embodiment of the

2

invention illustrated, it is shown as an angle bar extending vertically and diametrically across conduit 11 and secured thereto. A damper or vane 16 is pivoted to the bar 14 by a pivot 17, said pivot being disposed some distance above the center of damper 16 and conduit 11.

A member or housing 18 is provided, the same being of annular form and having a curved portion extending inwardly toward the axis of conduit 11, said member thus having a concave side which is directed toward wall

10. Member 18 has a peripheral flange 18a adapted to engage the inner side of wall 10 and be secured thereto by any suitable means, such as the circumferentially spaced screws 19. A second member 20 is provided, the same having an outer substantially semi-spherical portion 20a which has its concave side directed away from wall 10. The outer portions of members 18 and 20 or the portions farthest from wall 10 are in engagement and secured together, the same being rolled outwardly to form a bead 18b. This bead forms the outer edge of said members. Member 20 has an inner cylindrical portion 20b which extends into conduit 11. A part of the portion 20b is offset inwardly at the point 20c and conduit 11 extends over and fits about said part.

A plurality of brackets 22 are secured to the inner side of portion 20a, the same being shown as of annular form and extending outwardly in a substantially horizontal direction. A plate 23 engages the outer ends of brackets 22 and said brackets are secured to plate 23 and to portion 20a by the headed screws 24. Washers 25 underlie the heads of the screws 24 which secure plate 23. An electric motor 26 is secured to plate 23 by a plurality of circumferentially spaced bolts 28, said bolts extending through washers 29 disposed at each side of plate 23 and which will be made of rubber or other suitable insulating material which is preferably resilient. Motor 26 has a driving shaft 26a directed toward conduit 11, and a fan 30 is secured to shaft 26a. The fan 30 may be of any multibladed and efficient type. Plate 23 has a central opening 23a therein through which shaft 26a and a portion of a hub on said motor project. Plate 23 has a peripheral flange 23b offset outwardly to which is secured a cover 32. Cover 32 is shown as secured by a plurality of circumferentially spaced screws 33. Cover 32 has an outer peripheral flange from which extends a semi-dome portion, and said cover has a substantially cylindrical portion at its front. Cover 32 surrounds motor 26 and is spaced therefrom. The front cylindrical portion of cover 32 is provided with a multiplicity of slots or louvers 32b. It will be seen that members 18 and 20, plate 23, motor 26 and cover 32 are all coaxial with conduit 11. The inner portion of cover 32, plate 23 and fan 30 are disposed within the semi-spherical portion 20a.

In operation, the motor 26 will be driven and fan 30 will be rotated. Air will be now drawn outwardly through the conduit 11 as indicated by the arrow, and discharged from the room through the annular passage adjacent to ring 18b. The damper 16 will swing outwardly to permit this outward movement of air and when motor and fan are stopped, damper 16 will swing to a substantially vertical position and prevent cold air from the outside passing through conduit 11. It will be seen that the present structure is very compact. As stated, the bead 18b forms the outer edge of members 18 and 20 and any liquid or moisture which might collect on the inner surface of portion 20a will drip from said bead. It will be noted that cover 32 is separate from motor 26 and can be easily removed without disturbing motor 26. When the cover 32 is removed, the motor with fan 30 can then be removed with plate 23 by merely removing the screws 24. Most of the parts are made from sheet material which preferably will be aluminum. These

parts can be stamped out and thus made quite economically. The device also has great utility and efficiency as a roof exhaustor.

The device has been amply tested in actual practice, found to be very successful and efficient and is being commercially made.

It will of course be understood that various changes may be made in the form, details, arrangement and proportions of the parts, without departing from the scope of applicant's invention, which, generally stated, consists in a device capable of carrying out the objects above set forth, in the parts and combinations of parts disclosed and defined in the appended claims.

What is claimed is:

1. A ventilating device having in combination, a conduit adapted to be disposed in a passage extending through a wall, an annular member of sheet material and of semi-dome shape having a peripheral flange secured to said wall and extending outwardly away from said conduit with its concave side disposed toward said wall, a second annular member of sheet material having an outer semi-spherical portion and having an inner cylindrical tubular portion extending into said conduit and engaging the inner wall thereof so that air can pass through said conduit and tubular portion, said second member having its concave side directed outwardly or away from said wall, the outer portions of said first mentioned member and said second member being secured together, a plurality of circumferentially spaced brackets secured to said second member at the side thereof opposite said wall, a plate disposed at and engaging the outer ends of said brackets, bolts securing said plate to said brackets, a motor secured to said plate and having a driving shaft, a fan secured to said shaft and disposed in vertical alignment with said semi-spherical portion of said second member, said fan being constructed and arranged to draw air through said conduit and into and through said tubular portion of said second member, said air being discharged between the outer portion of said second member and said plate, and a cover removably secured to said plate enclosing said motor, said cover and plate forming a substantially closed chamber, said first mentioned member, second member, motor and fan being coaxial whereby said cover can be removed from said plate to expose said motor and said plate so that said motor and plate can then be removed.

2. The structure set forth in claim 1, the outer portions of said first mentioned member and second member being rolled into a bead which depends at the lower side of said members and forms a dripping edge for moisture or liquid.

3. The structure set forth in claim 1, said plate having a flange thereon offset outwardly to which said cover is secured, said plate and brackets being disposed within the semi-spherical portion of said second member.

4. A ventilating device having in combination, a conduit adapted to be disposed in a passage extending through a wall, a shell-like member of semi-dome shape having its concave side directed toward said wall and having a circular peripheral flange secured to said wall about said passage, a second annular member having a substantially semi-spherical shell-like outer portion disposed within said first mentioned member and having an inner cylindrical tubular portion extending therefrom into said passage and fitting in said conduit so that air can pass through said conduit and inner portion, the concave side of said second member being directed outwardly or away from said wall, the outer portions of said first mentioned member and second member being secured together, a plurality of angular-shaped and circumferentially spaced brackets secured to said semi-spherical portion and extending outwardly therefrom, a plate engaging and secured to said brackets and extending radially beyond the same, a motor at the outer side of said plate, said plate having a central opening through which a portion of said motor and the driving shaft thereof project, bolts securing said motor to said plate, a fan secured to said shaft and disposed in vertical alignment with said semi-spherical portion, said fan being constructed and arranged to draw air into and through said conduit and then through said tubular portion of said second member, said air being discharged between the outer portion of said second member and said plate, and a cover extending outwardly around and over the front of said motor and being spaced therefrom, said cover engaging said plate beyond said brackets and second bolts connecting said plate and cover beyond said brackets.
